UNITED STATES PATENT OFFICE.

PETER EGAN, OF BENNINGTON, VERMONT.

KNITTING-MACHINE-NEEDLE JACK.

Application filed January 8, 1921. Serial No. 435,899.

To all whom it may concern:

Be it known that I, PETER EGAN, a citizen of the United States, residing at Bennington, in the county of Bennington and State of Vermont, have invented certain new and useful Improvements in a Knitting-Machine-Needle Jack, of which the following is a specification.

This invention relates to knitting machine 10 needle jacks and is designed as an improvement on the jack shown in Patent 825,017 to W. T. Barratt dated July 3, 1906.

The object of the invention is to so construct a jack of this character whereby a 15 needle may be readily inserted in the jack without the use of pliers, pinchers or other tools thereby avoiding danger of breakage or bending of both the needle and the jack and facilitating the insertion of the needle.

Another object is to so construct a jack 20 that the needle will be reliably held engaged with the jack preventing lateral movement of the needle relatively to the jack and the consequent bending or breaking of both the 25 needle and the jack and insuring the regular engagement of the jack by its operating cam.

With these and other objects in view the invention consists in certain novel features of construction as hereinafter shown and 30 described and finally pointed out in the claims.

In the accompanying drawing:

Figure 1 represents a side elevation of a 35 jack constructed in accordance with this invention with the needle shown applied.

Fig. 2 is a transverse section taken on the line 2—2 of Fig. 1; and,

Fig. 3 is a rear edge view of the jack.

In the embodiment illustrated a needle 40 jack 1 and a spring barb needle 10 are shown, the needle and general structure of the jack corresponding to that shown in the patent above referred to. The jack 1 has the same S-shaped slot 2 extending transversely inward from the rear edge of the jack and the portion 3 of the rear edge in advance of said slot is made lower than the remaining edge a distance corresponding to the diameter of the shank 11 of the needle 10 so that the rear edge of the lower part of the 45 jack and the rear edge of the needle shank 11

will align when the needle and jack are connected. The needle 10 is equipped with a rightangularly extending S-shaped or reversely curved butt 12 of tortuous shape to 55 substantially fit the slot 2 of the jack.

To enable the reversely curved butt to be inserted in the slot 2 without necessitating the use of a tool the curved portion 4 is made sufficiently small to reduce the cam-like 60 gripping action between this element and the needle butt so that the butt may be readily inserted with the fingers in said slot. This is accomplished by cutting away the edge 3 of the jack adjacent the slot 2 for a 65 short distance as shown at 5 while said edge in advance of said cutaway portion is grooved longitudinally to form a seat 6 for the needle shank as shown in Figs. 1 and 3 so that the needle will be held against lateral 70 movement, the slot 2 operating to hold it against rearward movement.

It will thus be seen that this slight change in the jack accomplishes an important and novel result, greatly enhancing the value of 75 the jack by adapting it to reliably hold a needle firmly engaged therewith and to provide for the insertion of the needle by hand without the use of any tools whatever.

This jack not only reliably holds a needle 80 engaged therewith and permits its ready insertion without the use of tools but also provides for the ready removal of the needle by simply lifting it rearwardly a sufficient distance to clear the walls of the groove or seat 85 6 and then swinging it laterally to disengage its butt from the jack.

The preferred embodiment of the invention is disclosed in the drawings and set forth in the specification, but it will be 90 understood that any modifications within the scope of the claimed invention may be made in the construction without departing from the principle of the invention or sacrificing any of its advantages. 95

What I claim is:

1. A needle jack of the class described having a tortuous needle butt receiving slot extending transversely inward from its rear edge and a needle seat in said edge spaced 100 from said slot to hold a needle against lateral movement.

2. A needle jack having a tortuous needle butt receiving slot extending transversely inward from its rear edge, and a needle seat in said edge spaced from said slot, the portion of said edge between said slot and seat being cutaway to facilitate the engagement of the needle butt with the slot.
3. A needle jack having a substantially S-shaped needle butt receiving slot extending

transversely inward from its rear edge, and 10 a needle seat formed in said edge in advance of said slot, the portion of said edge between said seat and slot being cutaway to facilitate the insertion of the needle butt in the slot.

15 In testimony whereof, I affix my signature hereto.

PETER EGAN.
